DOLL

Abraham M. Katz, Brooklyn, N. Y., assignor to
Ideal Novelty & Toy Co., Brooklyn, N. Y., a cor-
poration of New York

Application January 9, 1933, Serial No. 650,751

8 Claims. (Cl. 46—40)

My invention relates to a new and improved doll.

One of the objects of my invention is to provide an improved doll having a head which is made of bendable rubber, said head being suitably reinforced so as to permit the insertion and use of movable eye-ball members.

Another object of my invention is to provide a doll having a head which is suitably reinforced at the front or face part, it being understood that said head is preferably made of resilient and bendable rubber.

Another object of the invention is to provide a doll having a head which is preferably made of resilient and bendable rubber, said head having an inner reinforcement which is made of hard rubber and metal or other suitable rigid material.

Other objects of my invention will be set forth in the following description and drawings which illustrate a preferred embodiment thereof, it being understood that the above general statement of the objects of my invention is intended merely to generally explain the same and not to limit it in any manner.

Fig. 1 is a front elevation, part of the head being represented as being broken away.

Fig. 2 is an inner elevation of the head, this view being partially in section.

Fig. 3 is a sectional view on the line 3—3 of Fig. 2.

Fig. 4 is a view similar to Fig. 2, showing the reinforcing insert.

Fig. 5 is a modification of Fig. 3.

Fig. 6 is a perspective view of the reinforcing insert.

The doll is provided with a body 1, arms 2 and legs 3, of any suitable type. The head 10 of the doll is mounted in any suitable manner upon the neck portion of the doll. The head 10 of the doll is generally made of resilient and bendable rubber composition, the front wall of said head being reinforced by a rigid insert 14, which is made of any suitable metal. This rigid insert 14 is provided with end walls 15, which have the curved shape shown in Fig. 6, and said end walls 15 are provided with metal reinforcing webs 17.

As shown in Fig. 4, when the reinforcing member 10 is applied to the head, the top wall of the reinforcing member 14 is above the eyes of the doll and said top wall is approximately near the top of the forehead of the doll.

The bottom wall of the member 14 is approximately at the level of the upper lip of the doll, so that the eye-sockets 11 of the head are located

intermediate the top and bottom walls of the member 14.

The end walls 15 are sharply inclined with reference to the top and bottom members of the insert, and said end walls 15 are imbedded in the cheeks of the head, so that the side walls of the head are suitably reinforced.

As shown in Fig. 3, the member 14 is preferably imbedded in a member 18 which is made of hard rigid rubber, and said member 18 is vulcanized to the inner surface of the front wall of the doll.

The hard rubber is preferably confined to the top and bottom webs of the member 14, so that the end walls 15 are preferably not imbedded in hard rubber. Said end walls 15 are imbedded, either wholly or partially, in the side walls or cheek portions of the head. As previously stated, the head of the doll is preferably made of resilient and bendable rubber. Likewise, the hard-rubber member 18 may be integral with an intermediate projection 19, in the embodiment shown in Fig. 3.

In order to manufacture the device, the reinforcing insert 14 may be assembled together with the hard-rubber member 18, the head 10 and the members 18 and 19 are then assembled in proper relationship, and the rubber head 10 and the hard-rubber member 18 are then simultaneously vulcanized. However, the article is not to be limited to any particular method of manufacture. Likewise, the member 18 could be vulcanized around the member 14, and the assembly of these parts with the head 19 could then be completed by vulcanizing the rubber material of the head 10 with the use of suitable pressure. Since the side-walls or cheek portions of the head 10 are vulcanized under pressure around the side walls of the insert, a very firm connection is secured, and no other connection is necessary.

The doll is provided with an eye-ball construction of any suitable type, a standard type being conventionally illustrated herein. The eye-ball members 12 are provided with rearwardly projecting and perforated lugs. The eye-ball members are turnably held in position by means of clips 16 which are made of resilient or spring wire. Said clips 16 are V-shaped and they have outer ends 20 which enter the wall of the head of the doll. Said ends 20 do not pass through the wall of the doll, and they preferably do not pass through the reinforcing webs 17, although they may enter openings or recesses in said webs 17.

In the embodiment shown in Figs. 2 and 3, the

adjacent laterally bent ends of the members 16 enter the member 19.

The eye-ball members 12 are provided with flanges 12a which limit the turning movement of 5 said eye-ball members. Said eye-ball members can be made of metal or any other suitable material. Each of them is provided with a weighted arm 13 so that the eye-balls are caused to turn when the head of the doll is tilted.

10 In the embodiment shown in Fig. 5, it can be assumed that the two separate members 16 which are shown in Fig. 2 are replaced by a single integral spring-wire member, whose shape and size is that of the two members 16 shown in Fig. 2. 15 This makes it possible to eliminate the member 19.

Up to the present time it has not been commercial to make a doll's head of resilient and bendable rubber and to provide said head with 20 movable eye-balls or eye-members.

According to the invention, the head of the doll is sufficiently reinforced so that in assembling the doll, the head of the doll can be handled with the same ease as though it were made out of rigid 25 composition or the like. This is due to the substantial reinforcement at the front and at the side walls of the head. Likewise, the reinforcement makes it possible to keep the eye-members in position, particularly if said eye-members are 30 movable.

In effect, the improved head has a reinforcement which is vulcanized to the front and/or to the side portions thereof, and this reinforcement is not to be limited to any particular material.

Generally speaking, my invention applies to any type of doll's head which is reinforced, and more particularly to a doll's head made of bendable rubber and which is reinforced. The invention is not to be limited to the use of the reinforcement at the part or parts which are shown in the specific embodiments illustrated herein, since for certain purposes the area for reinforcement may be varied and increased or diminished 45 in size.

One of the main objects of the invention is to sufficiently reinforce a doll's head made of bendable rubber so that said head can be handled, during the assembly of the doll, with the same 50 ease as though said head were rigid.

The head of the doll is provided with the usual opening at the bottom thereof, and said head can be connected to the body of the doll by any conventional means, such as a washer W, a hook 55 H, and an elastic E. The body B of the doll may be of any suitable type and this has a neck portion which enters the socket which is provided at the bottom of the hollow head 10.

I have shown a preferred embodiment of my 60 invention, but it is clear that numerous changes and omissions may be made without departing from its spirit.

I claim:

1. A doll's head made of bendable rubber, said 65 head having a rigid reinforcement which is located at the interior of the front wall of said head, said reinforcement having an open part between which the eyes of the head are located, said reinforcement having side means which are 70 vulcanized to the side walls of the head and which

ar at least partially imbedded in said side walls of the head.

2. A hollow doll's head having a reinforcement located therein, and associated with the front wall of said head, said reinforcement comprising hard rubber having rigid means imbedded therein, said reinforcement having upper and lower spaced portions between which the eye-ball sockets of the head are located.

3. A hollow doll's head made of bendable rubber, said head having an inner reinforcement vulcanized thereto, said reinforcement comprising rubber having rigid means imbedded therein.

4. A hollow doll's head made of bendable rubber, said head having an inner reinforcement vulcanized thereto, said reinforcement comprising rubber having rigid means imbedded therein, said rigid means comprising upper and lower spaced portions between which the eye-ball sockets of the head are located.

5. A doll's head made of bendable rubber, said head having eye-sockets, reinforcing means made of rubber which is harder than the rubber of which said head is made, said reinforcing means being vulcanized to the inner surface of the front 25 face of the head and being located above and below said eye-sockets, an annular reinforcing insert made of metal having portions thereof imbedded in said reinforcing means, the end walls of said insert being imbedded in the cheek portions of the head, and a rolling-eye set, said rolling-eye set having a pin upon which said set is mounted, and a support for said pin, said support being made of rubber which is vulcanized to the inner surface of the front of the head and which 30 is located between said eye-sockets.

6. A doll's head made of rubber and having eye-sockets, the inner surface of the front wall of said head having rubber reinforcement above and below the eye-sockets and also having rubber reinforcement intermediate said eye-sockets, a rolling-eye set mounted in said intermediate reinforcement, and a rigid insert having portions thereof imbedded in the reinforcement which is located above and below said eye-sockets, said 40 insert also having end portions which abut and reinforce the cheek portions of the head.

7. A doll's head made of rubber and having eye-sockets, the inner surface of the front wall of said head having rubber reinforcement above and below the eye-sockets and also having rubber reinforcement intermediate said eye-sockets, a rolling-eye set mounted in said intermediate reinforcement, and a rigid insert having portions thereof imbedded in the reinforcement which is 50 located above and below said eye-sockets, said insert also having end portions which abut and reinforce the cheek portions of the head, said end portions of the insert being inclined to the body thereof.

8. A doll's head made of bendable rubber, said head having eye-sockets, the inner surface of said head having a rubber reinforcement which is spaced from said eye-sockets, a rolling-eye set having a pin which is mounted in said reinforcement, said head also having a rigid metal insert whose side portions are imbedded in the cheek 65 portions of the head.

ABRAHAM M. KATZ.
